ALAN CALVERT, OF PHILADELPHIA, PENNSYLVANIA.

DUMB AND BAR BELL AND RING-WEIGHT.

1,044,018.

Specification of Letters Patent.

Patented Nov. 12, 1912.

Application filed April 14, 1911. Serial No. 621,053.

To all whom it may concern:

Be it known that I, ALAN CALVERT, a citizen of the United States, residing in the city and county of Philadelphia, State of Pennsylvania, have invented a new and useful Dumb and Bar Bell and Ring-Weight, of which the following is a specification.

My invention consists of improvements in an exercising device of the order of a dumb and bar bell and a ring weight, as will be hereinafter set forth, the novel features of the same being pointed out in the claims.

The invention is satisfactorily illustrated in the accompanying drawing, but the important instrumentalities thereof may be varied, and so it is to be understood that the invention is not limited to the specific arrangement and organization shown and described.

Figure 1 represents a partial diametrical section and a partial side elevation of a dumb and bar bell embodying my invention. Fig. 2 represents a face view of one of the sectional shells of the device taken at the diameter thereof. Fig. 3 represents a section of a portion on line $x-x$ Fig. 1. Fig. 4 represents an inner view of a cap employed in the device. Figs. 5 and 6 represent sections in opposite directions of said cap and adjacent portion of the shell to which it is applied. Fig. 7 represents a plan view of the shell at a pole thereof. Fig. 8 represents a side elevation of a portion of the device, and a section of a handle thereon adapting the device as a ring weight. Fig. 9 represents a side elevation of one of the weight plates employed. Fig. 10 represents an end view of a portion of one of the sections of the shell taken at the diameter thereof.

Similar letters of reference indicate corresponding parts in the figures.

Referring to the drawings:—A designates a spherical shell which is composed of the separate hemispherical sections B and C forming a hollow body. The section B is closed at what may be termed the diameter or equatorial line of the shell by the wall D, the corresponding portion of the section C abutting said wall. Passing through the poles of the shell A and the center of the wall D is the rod E which is continued outside of the shell so as to form the handle F of the device, said handle extending to the opposite shell where it joins or is continued into a similar rod E, the latter entering said opposite shell. The poles of the shell A

are depressed as at G, H, the depression G receiving the collar J, the inner portion of which is provided with a neck K which with said collar is fitted on the rod E, and secured to the latter by the bolt or rivet L, which is passed through said neck and collar. The depression H receives the nut M which is screwed upon a threaded portion of the adjacent end of the rod E, thus tightly seating the collar J on the face of the depression G and clamping together the sections B and C as one and firmly connecting said rod with the shell A.

In order to prevent the rotation of the collar J on the shell A, the face N of the depression G and the circumferential wall P of said collar are of elliptical form as shown in Fig. 3, the effect of which is evident. The section C contains the weight plates Q of different diameters, the same being placed one against the other and fitted centrally on the rod E they interlocking with each other by means of the projecting tongues R and grooves S one of each of which is formed on the respective plate, so that the tongue of one plate enters the groove of the contiguous plate. The wall D has on its side toward the plate Q, the tongue T which is adapted to enter the groove S of the adjacent plate.

In the periphery of the wall D are the recesses U and on the inner face of the section C are the segmental beads V the latter extending from the diameter of the section to the pole of the same. In the peripheries of the plates Q are recesses W, it being noticed that said beads V are adapted to enter said recesses U of the wall D, and said recesses W of the plates Q by which means the plates are interlocked with each other and also with the wall D and the section C, the sections B C being also interlocked with each other; all in such manner that the plates are prevented from rotating in the section C, and the sections B C are prevented from rotating on each other, the plates as is evident being compactly held together comparatively as a solid structure with the section C and so are without liability to rattle or shift in any direction.

The section B is adapted to contain shot, pellets or pieces of loose material for adjustably loading or weighting the shell as heretofore practiced. Access is had to the interior of said section through the opening or inlet X which is closed by the cap or

stopper Y, the wall of said opening having outturned recesses Z therein and said cap having on its inner side the tongues Y' which are adapted to be passed through 5 said recesses into the section while the cap is seated on said inlet X on the exterior of the section. Then when the cap is partly rotated, the tongues turn with the same and leave the recesses Z when they ride on and 10 across the inner side of the wall of said inlet and so lock the cap to the shell. Secured to the inner side of said cap is the plate spring Y², whose ends are adapted to be interposed between the cap and the face of the opening 15 X and so create friction on the cap and prevent rotation of and release of the latter, but when the cap is properly rotated until the tongues Y' register with the recesses Z, the cap is no longer controlled by the wall 20 around the inlet and so may be withdrawn and access provided to the interior of the section B. Secured to the wall D and the pole of the section B at the depression G is the sleeve E', the rod E being adapted to 25 pass through the same whereby should said rod be removed the openings in said wall and pole will be closed from within the section so as to prevent the shot or loose 30 weights in said section from escaping through said opening.

Referring to Fig. 8 when the device is intended as a ring weight, there is connected with the rod E, the handle E² shown partly broken off, at the base of which is the collar 35 J shown in dotted lines, the same being similar to the collar shown in Figs. 1 and 3, said collar being seated in the depression G in said figures. The handle portion F of the rod as such is dispensed with, it being 40 evident that the shell with its interior weights may be carried by the handle E² and manipulated by the same as a ring weight for exercising purposes.

Having thus described my invention what 45 I claim as new and desire to secure by Letters Patent, is:—

1. In an exercising device, a hollow spherical body, a plurality of weight plates therein, a head on the interior face of said body, 50 grooves in the peripheries of said plates, and tongues and grooves respectively on and in the contiguous faces of said plates being between the peripheries and centers of said plates.

2. In an exercising device, a hollow spherical body formed of separate sections, means for connecting the same, a closing wall on one of said sections on the diametrical portion thereof, means for interlocking said sections, a plurality of weight plates of different diameters in the other section, a bead on the inner face of the weight-receiving section, said plates having grooves in the peripheries thereof adapted to receive said bead, and tongues and grooves on and in the contiguous faces, said tongues and grooves being between the peripheries and centers of said plates. 55 60 65

3. In an exercising device, a hollow spherical body, a bead on the interior face thereof, 70 and a weight plate in said body, the plate having on the circumference thereof a groove adapted to receive said bead for interlocking said plate with said face of the shell. 75

4. In an exercising device of the character stated, a hollow spherical body formed of separate sections, means for connecting the same, a bead on the inner face of one of said sections, and a groove on the diametrical portion of the other section, said bead being adapted to enter said groove for interlocking the sections and preventing rotation of the latter one on the other. 80 85

5. In an exercising device of the character stated, a hollow body, an opening being formed therein, a rotatable cap adapted to close said opening, means for retaining the cap in closed position and a plate spring on the inner side of said cap secured thereto, 90 said spring being adapted to rotate with said cap and its ends engaging the face of said opening. 95

6. In an exercising device of the character stated, a hollow body having a partition wall, an opening in the outer wall of the body, said opening having out-turned recesses, a cap fitted to said opening, diametrically disposed arms extended beyond the opposite edges of said cap and adapted to 100 enter said recesses, and a spring disposed at an angle to said arms and adapted to lie between the cap and the wall about said opening.
